L. C. DEAVER.
RAILROAD RAIL COUPLING.
APPLICATION FILED DEC. 12, 1919.

Patented Aug. 17, 1920.

Inventor
L. C. Deaver

By *Alvarez Jr.*
Attorney

UNITED STATES PATENT OFFICE.

LUTHER C. DEAVER, OF CULBERSON, NORTH CAROLINA.

RAILROAD-RAIL COUPLING.

1,349,607.

Specification of Letters Patent. Patented Aug. 17, 1920.

Application filed December 12, 1919. Serial No. 344,448.

To all whom it may concern:

Be it known that I, LUTHER C. DEAVER, a citizen of the United States, residing at Culberson, in the county of Cherokee and 5 State of North Carolina, have invented certain new and useful Improvements in Railroad-Rail Couplings; and I do hereby declare the following to be a full, clear, and exact description of the invention, such as 10 will enable others skilled in the art to which it appertains to make and use the same.

This invention relates to new and useful improvements in railroad rail couplers and has for one of its objects the provision of a 15 locking plate secured to the railroad joint by a single fastening means and is provided with a series of locking elements adapted to fasten a plurality of bolts of the railroad joint thereby rendering a saving of time 20 and labor in securing the parts of the joint together and also whereby the bolts are positively locked.

Another object of this invention is the provision of a railroad rail coupler of the 25 above stated character, which shall be simple, durable and efficient, and which may be manufactured and sold at a comparatively low cost.

With these and other objects in view as 30 will become more apparent as the description proceeds, the invention consists in certain novel features of construction, combination, and arrangement of parts as will be hereinafter more fully described and 35 claimed.

For a complete understanding of my invention, reference is to be had to the following description and accompanying drawing, in which:

40 Figure 1 is a side elevation of a railroad rail joint illustrating a coupler applied thereto and constructed in accordance with my invention,

Fig. 2 is a side elevation of the locking 45 plate illustrating the locking elements thereon,

Fig. 3 is a plan view of one of the bolts used in the joint.

Referring in detail to the drawings, the 50 numeral 1 indicates as an entirety a railroad rail joint in which the ends 2 are arranged in abutting engagement with each other and are secured together by fish plates 3 provided with openings 3' to receive bolts 4 55 that extend through the web portions of the ends of the rails. The bolts 4 have formed

on one of their ends heads 5 while their other ends are provided with openings 6.

The joint 1 is provided with a locking bolt 7 provided with a usual screw threaded end and said bolt is arranged in a plane above the bolts 4 and at a point intermediate the series of bolts 4 and extends through a slot 8 of a locking plate 9. The locking plate 9 is secured to the joint by a lock nut 10 of any desired type threaded to the bolt 7. The lower edge of the locking plate 9 is provided with a series of locking elements 11 arranged in horizontal alinement with each other and are adapted to extend through the openings 6 in the bolts 4 so as to prevent the withdrawal of the bolts 4 from the joint 1. Some of the locking elements 11 are formed on the lower edge of the locking plate 9 by having the plate cut away as illustrated at 12 and which cut-away portions are in the form of notches having their upper walls 13 curved while their lower walls are disposed straight to form the locking elements 11. The locking elements 11 are rounded so that they can be readily inserted through the openings 6 in the bolts 4. One end of the locking plate 9 has formed thereon an extension 15 which is rounded to form a locking element similar to the locking elements 11 and is adapted to pass through the end bolt 5 of the series of bolts 4.

From the foregoing description it will be noted by removing the lock nut 10, the locking plate 9 may be shifted longitudinally in one direction to disengage the locking elements 11 from the bolts 4 and said locking plate then is free to be removed from the bolt 7. To disconnect the rails of the joints 95 the bolts 4 and 7 are removed from the rails and fish plates freeing the rails so that they can be separated. It is further to be noted that the locking plate can be readily moved into a locking position to lock the various 100 bolts against withdrawal from the joint and also that the locking plate is held onto the joint by a single fastening means.

While I have shown and described the preferred embodiment of my invention, it 105 will be understood that minor changes in construction, combination, and arrangement of parts may be made without departing from the spirit and scope of the invention as claimed.

110 What is claimed is:—
A railroad coupler including a joint hav-

ing bolts provided with openings, a locking plate, means detachably securing the locking plate to the joint, said locking plate having a series of notches in its lower edge 5 to form horizontally disposed locking elements adapted to extend through the openings of some of the bolts, and a locking element formed on the end of the locking plate and in alinement with the first named lock-

ing elements and adapted to extend through 10 the openings in the end bolt of the series of bolts.

In testimony whereof I affix my signature in presence of two witnesses.

LUTHER C. DEAVER.

Witnesses:

C. L. BUTT,
PAT HARALSON.
